UNITED STATES PATENT OFFICE.

CHARLES W. HUBBARD, OF WESTON, MASSACHUSETTS.

TWISTING AND WINDING APPARATUS.

Application filed May 19, 1923, Serial No. 640,109. Renewed May 11, 1926.

This invention relates to twisting and winding apparatus of that type comprising a yarn receiver and a winding head which are rotatable relative to each other and are arranged so that the winding head lays the yarn in the yarn receiver in loops forming layers extending transversely to the axis of rotation. An example of a winding machine of this general type is illustrated in my Patent No. 1,258,412, dated March 5th, 1918.

One feature of the present invention relates to means whereby the spacing of the loops in each layer can be varied so that the loops may be laid closer to or further from each other as desired.

Another feature of the invention relates to an improved means for supporting and operating the winding head by which the yarn is laid.

Still another feature of the invention relates to an improved manner of operating and controlling the cam which in turn controls the laying arm and compensating arm.

Still another feature of the invention relates to a novel means for controlling said cam by which the relative rotative movement between the cam and the housing and yarn container can be varied thereby varying the spacing of the loops.

Still another feature of the invention relates to means whereby this relative spacing of the loops and the relative motion between the winding head and the yarn receiver by which the amount of twist put into the yarn is determined can be controlled from the end of the frame.

Other features of the invention relate to various improvements which will be more fully hereinafter set forth.

In the drawings wherein I have illustrated a selected embodiment of my invention, Fig. 1 is a vertical sectional view through a winding head and the upper part of a yarn receiver embodying my invention, said view being taken on the broken line 1—1, Fig. 4;

Fig. 2 is an enlarged view showing the driving means for the yarn receiver, winding head and yarn-laying cam;

Fig. 3 is a top plan view of the driving mechanism shown in Fig. 2;

Fig. 4 is a section on the line 4—4, Fig. 1;

Fig. 5 is a section on the line 5—5, Fig. 1;

Fig. 6 is a section on the line 6—6, Fig. 1;

Fig. 7 is a section on the line 7—7, Fig. 1;

Fig. 8 is a view showing the gearing at

the end of the frame by which the relative speeds of the shafts 15, 30 and 51 may be varied;

Fig. 9 is a section on the line 9—9, Fig. 8; 60

Fig. 10 is a section on the line 10—10, Fig. 8;

Fig. 11 is a section on the line 11—11, Fig. 8.

In the drawings 1 indicates a rotatable 65 yarn receiver preferably having a cylindrical shape and in which the yarn mass 2 is laid up in loops forming layers extending transversely to the axis of rotation all as usual in winding and twisting machines of 70 this type. This yarn receiver is supported and rotated by a hollow shaft 3 through the bore 4 of which the yarn is delivered to the yarn mass, said shaft being rotatably mounted in a suitable frame 5. 75

I have herein shown a ball bearing 6 between the shaft and the frame. The yarn receiver 1 is secured to the shaft 3 through the means of a housing 7 in which the winding head is received, this housing being 80 keyed to the shaft 3 as shown at 8. The yarn receiver 1 will be supported on a suitable step bearing and it is connected to the housing 7 so as to rotate therewith by means of one or more spring-pressed locking pins 85 9 carried by the housing and adapted to enter recesses 10 in the upper edge of the receiver all as shown in my co-pending application Serial No. 572,441, dated July 3, 1922. 90

As stated above the shaft 3 is rotatable and for this purpose it has a gear 11 fast thereon which meshes with and is driven by a gear 12, the latter having rigid therewith a bevel gear 13 which meshes with and is driven by a bevel gear 14 on a shaft 15 extending longitudinally of the frame. This shaft 15 is the shaft to which power is applied and from which the machine is operated.

The winding head by which the yarn 100 mass 2 is laid up is received within the housing 7 and it comprises the usual winding plate 16 which rests on the yarn mass and is formed with a radial slot 160 through which the yarn 161 is delivered to the yarn mass, such yarn being traversed in the slot by means of an oscillating yarn-laying arm 17 105 all as usual in machines of this type.

Associated with the yarn-laying arm 17 is a compensating arm 33 which also oscillates horizontally and which serves to maintain an even tension on the yarn. The yarn 110

161 passes from the bore 4 in the shaft 3 to the eye 162 at the end of the compensating arm and thence passes to the eye 163 in the end of the yarn-laying arm and from the 5 latter is delivered to the slot 160 of the winding plate, all as usual in winding heads of this type. Said winding head also includes a cam for oscillating the yarn-laying arm and the compensating arm as will be presently described. This winding head is supported on the lower end of the shaft 3 and is rotatable thereabout.

The winding plate 16 of the winding head is secured to a head member 18 by means 15 of suitable posts 19 and said head member is supported and rotatably mounted on the shaft 3, through the medium of ball bearings 20. The head member is retained in place by means of a nut 21 which is screw- 20 threaded to the lower end of the shaft 3. The winding head including the head member 18 and winding plate 16 is given a rotative motion relative to the yarn receiver 1 by means of the following mechanism.

25 The head member 18 is provided with an internal gear 22 which meshes with gears 23 formed on the lower end of studs 24 that are journaled in the bridge portion 25 of the housing 7, said studs 24 having fast on 30 their upper ends gears 26 which mesh with a gear 27 loosely mounted on the shaft 3. This gear 27 is a long gear which projects through the cap plate 28 of the housing and which meshes with and is driven by a controlling gear 29 which in turn is driven from a shaft 30 that extends longitudinally of the machine through suitable intermeshing gears 31, 32, the latter being rigid with the gear 29.

40 The yarn-laying arm 17 and the compensating arm 33 are supported by vertical rock shafts 34, 35 which in turn are journaled in the head member 18 and these rock shafts are given their oscillating movement through 45 a cam member 36, which is also supported by the shaft 3 and is rotatable thereabout.

The cam member by which the compensating arm 33 and yarn-laying arm 17 are oscillating is provided with a double cam 50 groove comprising the two cam grooves 39 and 42 which are formed on the under face of the cam member, one of said cam grooves controlling the yarn-laying arm 17 and the other controlling the compensating arm 33.

55 The rock shaft 34 of the yarn-laying arm has at its upper end a crank pin 37 carrying a roll 38 that operates in the cam groove 39 and the rock shaft 35 for the compensating arm 33 also has at its upper end a crank 60 arm 40 carrying a roll 41 that operates in the cam groove 42, these grooves being so shaped as to give the yarn-laying arm the necessary oscillating movement to lay the yarn in the loops and to give the compensating arm 17 the necessary oscillating movement

to maintain the yarn under a substantial uniform tension.

The cam is given a rotation relative to the housing member as usual in machines of this type and for this purpose said cam has 70 rigid therewith a gear 43 which meshes with gears 44 formed on studs 45 which are journaled in the bridge portion 25 of the housing, said studs having rigid therewith gears 46 which mesh with a gear 47 supported by 75 and free to revolve on the shaft 3. This gear 47 is shown as having a hub portion 48 extending through the gear 27 and on which it is rotatably mounted, said hub portion carrying at its upper end a gear 49 which 80 meshes with and is driven by a gear 50. The gear 50 in turn is driven from a shaft 51 that extends longitudinally of the machine and for this purpose the gear 50 has rigid therewith a worm or spiral gear 52 meshing 85 with and driven by a complementary gear 53 fast on the shaft 51.

The structure herein shown is further provided with capstans for drawing the yarn through the hollow shaft 3 and delivering it to the compensating arm and yarn-laying arm thus relieving the latter of the work of pulling the yarn into the machine. There are two such capstans indicated at 101 and 102, said capstans being situated below the head 18 and substantially in the plane of the lower end of the shaft 3. These capstans are fast on shafts 103 and 104 which are journaled in the lower portion of the head and each shaft has fast thereto at its upper end a gear 105 which can be driven either from the cam member 36 or from the shaft 3. In the construction shown said gear 105 is driven from the cam member 36 and for 90 this purpose the cam member has rigid therewith a gear 106 with which the gear 105 intermeshes. The rotation of the winding head relative to the cam 36 or the housing 7 will thus rotate the capstans 101, 102 and the latter will operate to draw the yarn positively through the bore 4 of the tube 3 and deliver it to the compensating arm. With 95 this arrangement it will be noted that the capstans are located within the winding head and in close proximity to the compensating arm and yarn-laying arm.

When a machine of this type is in operation the yarn container 1 with the yarn therein is rapidly rotating at one speed and the winding head 18 within the housing 7 is rotating at a different speed while the cam 36 is rotating at a speed different from that of either the housing or the winding head. The yarn, therefore, will be drawn into and laid on the yarn mass because of the fact that the winding head with its winding plate 16 is rotating at a different rate of speed from that of the yarn receiver and the oscillating motion of the yarn-laying arm 17 will cause the yarn to be laid in loops 100 105 110 115 120 125 130

extending transversely to the axis of rotation, said loops being laid progressively so as to form layers.

The amount of twist which is put into the 5 yarn depends upon the relation between the speed of rotation of the yarn receiver 1 and the rate at which the yarn is wound; and the rate at which the yarn is wound is determined by the relation between the 10 rotation of the yarn receiver and that of the winding head. This relation is determined by the relative speed of rotation of the shafts 15 and 30 so that by varying the relative speed with which these shafts rotate the 15 amount of twist and the speed which which the yarn is laid can be determined.

The spacing of the individual loops of each layer is determined by the relative speeds of rotation of the cam 36 and the yarn mass, 20 (the latter having the same speed of rotation as the housing and yarn container) and this in turn is determined by the relation between the speed of rotation of the shafts 15 and 51. If the difference between the speed 25 of rotation of the cam 36 and the yarn is increased then the loops will be laid an increased distance apart and if this difference is diminished then the loops will be laid nearer together.

30 While the above description relates to a winding and twisting unit comprising a yarn receiver and its winding head yet it will be obvious that any number of such winding and twisting units may be supported 35 on the same frame in which case each one may be geared to the shafts 15, 51 and 30 so that said shafts will control all of the individual units.

One arrangement by which the shafts 15, 40 51 and 30 can be utilized to operate a number of winding and twisting units is shown in Fig. 3, wherein a set of four winding and twisting units are grouped about each set of gears 12, 50 and 29 and wherein the shafts 45 15, 51 and 30 are arranged to operate a plurality of sets of gears 12, 50 and 29. The number of sets of such gears will depend entirely upon the length of the frame.

Where this arrangement is employed all 50 the winding units of the several groups will operate alike and the same amount of twist will be put in the yarn which is delivered to all of the winding units, and the spacing of the loops in all the yarn receivers can be varied simultaneously by merely varying the relative speeds of the shafts 15, 30 and 51 as above described.

I have provided herein means situated at the end of the frame 5 by which the relative speeds of these shafts can be varied thereby to secure variations in the degree of twist put into the yarn and also to secure variations in the spacing of the loops as they are laid. This controlling mechanism is illustrated in Figs. 3, 8, 9, 10 and 11,

and it comprises a system of gearing placed in a gear box at the end of the frame and connecting the shafts 15, 30 and 51, which in many respects is similar to the gearing in the winding head.

It will be remembered that the shaft 15 is the shaft which has the power applied thereto so that said shaft constitutes the prime mover for the moving parts of the machine. This shaft 15 is rotating at a 75 constant speed. It will also be remembered that said shaft 15 runs the length of the frame and drives the housings of the various units. This driving shaft 15 is operatively connected at one end of the frame to a gear 80 79 which is situated in the gear box at the end of the frame (see Figs. 8 and 11), the connection between the shaft 15 and the gear 79 being such as to cause said gear 79 to rotate synchronously with the shaft 15. 85 This gear connection comprises a gear 55 fast on the shaft 15 and meshing with a gear 58 which is fast on a sleeve 63 journaled in the end of the frame. The gear 58 in turn meshes with a gear 81 which is fast on a shaft 80 journaled in the end of the frame, said shaft 80 having the gear 79 fast thereon. The train of gears connecting the shaft 15 to the gear 79 thus comprises the gears 55, 58, 81 and shaft 80 and the gear 79 90 rotates synchronously with the shaft 15.

A change gear connection is interposed between the gear 79 and the shaft 30 by which the relative speed of the shaft 30 and the gear 79 may be varied and since the gear 79 rotates synchronously with the shaft 15 this change gear device provides means for varying the speed of the twist regulator shaft 30 relative to the main driving shaft 15. The twist regulator shaft 30 which also 105 extends the length of the frame has a gear 74 rigid therewith which meshes with a gear 75 mounted on a stud 76 which is adjustably mounted in brackets 77. The stud 76 also has a gear 78 thereon which meshes with the gear 79. The bracket 77 is provided with a slot 82 in which the stud 76 is adjusted and the gear 78 is removably mounted on the stud. With this construction the gear 78 may be removed and replaced by a larger 110 or smaller gear which may be brought into mesh with the gear 79 by proper adjustment of the stud 76. This provides a change gear construction by which the relative speed between the gears 74 and 79 can be 115 varied thereby varying the relative speed between the driving shaft 15 and the twist regulator shaft 30. By thus changing the speed of the shaft 30 relative to the driving shaft 15 a corresponding change is effected 120 in the amount of twist which is put into the yarn.

The regulation of the spacing of the loops is secured by varying the speed of the shaft 51 relative to the shafts 15, 30 and 130

this is arrived at by combining the motion of the shafts 15 and 30 and then combining the resultant motion again with that of the shaft 15 and by means of suitable change 5 gears.

It will be remembered that the shaft 15 is connected to and drives the sleeve 63 through the gears 55 and 58. This sleeve or hollow shaft 63 has fast thereto at its 10 end a gear 64 which forms one of a pair of loop-regulating gears, this gear 64 being driven directly from the driving shaft 15 at a speed of unvarying ratio with that of the driving shaft.

15 The other gear of the pair of loop-regulating gears is the gear 62 which has the same pitch diameter as the gear 64 and is located co-axially therewith, said gear 62 being mounted on a shaft 61 which extends 20 through the hollow shaft 63. This shaft 61 has fast thereto a gear 60 which meshes with a gear 57 on the loop-regulating shaft 51.

25 The gears 62 and 64 are connected through a hunting gear 65 which meshes with both gears and is rotatably mounted on a stud 66 that is adjustably carried in a plate 67 formed on a sleeve 68 that is journalled in the frame. The rotation of the gears 62 30 and 64 is differentiated primarily by having a different number of teeth in said gears so that at each revolution thereof one of the gears will gain or lose slightly with reference to the other gear, and secondarily 35 by providing means for rotating the plate 67 through the joint action of the shafts 15 and 30.

40 The sleeve 68 has rigid therewith an internal gear 69 which meshes with and is driven by a pinion 70 on a shaft 71 carried by the gear 58, which it will be remembered 45 meshes with the gear 55 fast on the main drive shaft 15. The shaft 71 also carries a gear 72 which meshes with a gear 73 rigid with a gear 59 that in turn meshes with a gear 56 rigid with the twist-regulating shaft 30. The ratio of the gearing 73, 72, 70, 69 must be the same as the ratio in each 50 winding and twisting unit between the gears 27, 26, 23, 22. This being so no matter what change is made in the change gears 75 and 78 the ratio in the gear box at the end of the frame between the gears 64 and 67 will be the same as the ratio between 55 the shaft 3 of each individual winding and twisting unit and its winding head 18 and the number of loops which are laid in each layer will be represented by the ratio between the 60 number of teeth in the gears 62 and 64 corresponding to the similar gears used in the individual winding heads and described in the above-mentioned patent. The hunting gear 65 has been described as adjustably mounted on the plate 67. This is to provide 65 for changing the gears 62 and 64 so as

to substitute other gears therefor of a larger or smaller diameter and with teeth having a greater or less difference in number. In order to balance the structure a balance weight 93 is provided which is of 70 a size to balance the weight of the hunting gear 65. This balance weight is supported on the plate 67 diametrically opposite to the gear 65 and is mounted on a stud 94 which is adjustably mounted on the plate 75 80 so as to permit the weight to be adjusted as the hunting gear is adjusted.

The studs 66 and 93 may be adjustably supported in the plate 67 in any appropriate way. As herein shown said plate is 85 formed with slotted ears 92 in the slots 91 of which the studs are adjustably mounted.

I claim.

1. In a twisting and winding machine, the combination with a hollow shaft, of a housing fast thereon, a yarn container secured to the housing, a winding head situated within the housing and journalled on the shaft, said winding head being constructed to wind yarn delivered through the hollow shaft in loops lying in planes transverse to the axis of rotation, means to rotate the shaft and yarn container thereby to twist the yarn, means to produce a relative rotary motion between the yarn container and the winding head thereby to lay the twisted yarn, and means for varying the spacing of the loops in any layer. 90 95

2. In a winding and twisting apparatus, the combination with a hollow shaft, of a housing fast thereon, a yarn container secured to said housing, a winding head situated within the housing and rotatably mounted on the shaft, an oscillating yarn-laying arm carried by the winding head, 100 a cam for oscillating said arm, means to rotate the shaft and yarn container thereby to twist the yarn, means to produce a relative motion between the yarn container and the winding head thereby to lay the yarn, 105 means for rotating the cam, and means for varying the relative speed of rotation between the cam and the housing. 110

3. In a twisting and winding apparatus, the combination with a frame, of a plurality 115 of twisting and winding units supported thereby and each comprising a rotary yarn container and means to lay yarn in said yarn container in loops forming layers extending transverse to the axis of rotation, and means 120 for varying simultaneously the spacing of the loops in all the units.

4. In a winding and twisting apparatus, the combination with a hollow rotatable shaft, of a yarn container secured thereto for rotation therewith, a winding head loosely mounted on said shaft and situated within the housing, said winding head having a gear rigid therewith, a gear loose on 125 said hollow shaft, planetary gearing car- 130

ried by the housing and connecting the gear loose on the shaft with the gear rigid with the winding head, means for rotating the shaft, and means for rotating the loose gear.

5. In a winding and twisting apparatus, the combination with a hollow rotatable shaft, of a yarn container secured thereto for rotation therewith, a winding head loosely mounted on said shaft and situated within the housing, said winding head having an internal gear rigid therewith, a gear loose on said hollow shaft, a planetary gearing carried by the housing and connecting the gear loose on the shaft with the gear rigid with the winding head, means for rotating the shaft, and means for rotating the loose gear.

6. In a winding and twisting apparatus, the combination with a frame, of a hollow shaft rotatably mounted therein, a housing fast on the shaft, a yarn container secured to the housing, a winding plate rotatably mounted on the shaft and having a yarn-laying slot, an oscillating yarn-laying arm, a cam for oscillating said arm, a gear rigid with said cam, another gear rigid with the winding plate, two gears loosely mounted on the shaft, planetary gearing connecting one of said loose gears to the gear rigid with the winding plate, and the other loose gear with the gear rigid with the cam and means for rotating the shaft, and means for rotating each of the loose gears.

7. In a winding and twisting apparatus, the combination with a frame, of a hollow shaft rotatably mounted therein, a housing fast on the shaft, a yarn container secured to the housing, a winding plate rotatably mounted on the shaft and having a yarn-laying slot, an oscillating yarn-laying arm, a cam for oscillating said arm, a gear rigid with said cam, another gear rigid with the winding plate, two gears loosely mounted on the shaft, a planetary gearing connecting one of said loose gears to the gear rigid with the winding plate, and the other loose gear with a gear rigid with the cam and means for rotating the shaft, and means for rotating each of the loose gears, said means being constructed to produce different relative speeds of rotation of the loose gears.

8. In a winding and twisting apparatus, the combination with a frame, of a hollow shaft rotatably mounted therein, a housing fast on the shaft, a yarn container secured to the housing, a winding plate rotatably mounted on the shaft and having a yarn-laying slot, an oscillating yarn-laying arm, a cam for oscillating said arm, a gear rigid with said cam, another gear rigid with the winding plate, two gears loosely mounted on the shaft, planetary gearing connecting one of said loose gears to the gear rigid with the winding plate, and the other loose gear with the gear rigid with the cam and

means for rotating the shaft, two driving gears for rotating the two loose gears, and means whereby these driving gears may be operated at different relative speeds.

9. In a winding and twisting apparatus, the combination with a frame, of a hollow shaft rotatably mounted therein, a yarn container rigid with the shaft, a winding head including a winding plate rotatably mounted on the shaft, an oscillating yarn-laying arm carried by the winding head, a cam for oscillating said arm, two loose gears rotatably mounted on said shaft, planetary gearing connecting one loose gear to the winding head, other planetary gearing connecting the other loose gear to the cam, and three driving gears for rotating the shaft and the two loose gears respectively.

10. In a twisting and winding machine, the combination with a frame, of a plurality of twisting and winding units supported thereby and each comprising a rotatable yarn container, a winding head for laying the yarn in said yarn container in loops forming layers extending transverse to the axis of rotation, and a cam for controlling the laying of the loops, three shafts extending longitudinally of the frame, gearing connecting one shaft to each yarn container, other gearing connecting another of the shafts to each winding head, and still other gearing connecting the third shaft to each cam.

11. In a twisting and winding machine, the combination with a frame, of a plurality of twisting and winding units supported thereby and each comprising a rotatable yarn container, a winding head for laying the yarn in said yarn container in loops forming layers extending transverse to the axis of rotation, and a cam for each winding head controlling the laying of the loops, three shafts extending longitudinally of the frame, driving connections between one shaft and each of the yarn containers, other driving connections between another shaft and each of the winding heads, and still other driving connections between the third shaft and each of the cams, and means for varying the relative speeds of said shafts.

12. In a twisting and winding machine, the combination with a frame, of a hollow shaft rotatably mounted therein, a housing fast on the shaft, a yarn container secured to the housing, a winding head situated within the housing and journaled directly on and supported by said shaft and constructed to lay yarn in loops forming layers extending transverse to the axis of rotation.

13. In a winding and twisting apparatus, the combination with a frame, of a plurality of twisting and winding units supported thereby and each comprising a rotatable yarn container, a winding head for laying the

6
yarn in each yarn container in loops forming layers extending transverse to the axis of rotation, and a cam for controlling the laying of the loops, three shafts extending longitudinally of the frame, gearing connecting one shaft to each yarn container, other gearing connecting another of the shafts to each winding head, and still other gearing connecting the third shaft to each cam, and means at the end of the frame by which the relative speeds of the shafts can be determined.

14. In a winding and twisting apparatus, the combination with a frame, of a plurality of twisting and winding units supported thereby and each comprising a rotatable yarn container, a winding head for laying the yarn in each yarn container in loops forming layers extending transverse to the axis of rotation, and a cam for controlling the laying of the loops, driving connections by which all the yarn containers are rotated in unison, all the winding heads are rotated in unison and all the cams are rotated in unison, and means at the end of the frame by which the spacing of the loops in all the units may be varied simultaneously.

15. In a winding and twisting apparatus, the combination with a hollow shaft, of a housing fast thereon, a yarn container secured to said housing, a winding head situated within the housing and rotatably mounted on the shaft, an oscillating yarn-laying arm carried by the winding head, a cam for oscillating said arm, means for rotating the housing, winding head and cam at different relative speeds, and yarn-feeding means actuated by said cam.

16. In a winding and twisting apparatus, the combination with a hollow shaft, of a housing fast thereon, a yarn container secured to said housing, a winding head situated within the housing and rotatably mounted directly on the shaft, an oscillating yarn-laying arm carried by the winding head, a cam for oscillating said arm, means for rotating the housing, winding head and cam at different relative speeds, and yarn-feeding capstans actuated by said cam.

17. In a winding and twisting apparatus, the combination with a rotatable yarn container, adapted to contain a yarn mass, of a winding head for winding a yarn mass therein, said winding head comprising a slotted winding plate resting on the yarn mass, an oscillating yarn-laying arm, a cam for oscillating said arm and yarn-feeding means actuated by said cam.

18. In a winding and twisting apparatus, the combination with a hollow shaft, of a housing fast thereon, a yarn container secured to the housing, the yarn to be wound being delivered to the container through said shaft, a winding head situated within the housing and rotatably mounted on said shaft, said winding head including a slotted winding plate resting on the yarn mass, an oscillating yarn-laying arm, a cam for oscillating said arm, and yarn-feeding capstans actuated by said cam and acting on the yarn between the hollow shaft and the yarn-laying arm.

In testimony whereof, I have signed my name to this specification.

CHARLES W. HUBBARD.
